CLAIM

The ornamental design for a control box, as shown and described.

DESCRIPTION

FIG. 1 is a perspective view of a first embodiment of a control box showing my new design;
 FIG. 2 is another perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof;
 FIG. 9 is an enlarged view of portion 9 shown in FIG. 1;
 FIG. 10 is a perspective view of a second embodiment of the control box showing my new design;
 FIG. 11 is another perspective view thereof;
 FIG. 12 is a front elevational view thereof;
 FIG. 13 is a rear elevational view thereof;
 FIG. 14 is a left side elevational view thereof;
 FIG. 15 is a right side elevational view thereof;
 FIG. 16 is a top plan view thereof; and,
 FIG. 17 is a bottom plan view thereof.

The broken lines in the drawings depict portions of the control box that form no part of the claimed design. The broken lines immediately adjacent to shaded surfaces form a boundary of the claim.
